UNITED STATES PATENT OFFICE.

ELBRIDGE W. STEVENS, OF BALTIMORE, MARYLAND.

IGNITER FOR EXPLOSION-ENGINES.

968,280.

Specification of Letters Patent. Patented Aug. 23, 1910.

Application filed October 11, 1909. Serial No. 522,138.

To all whom it may concern:

Be it known that I, ELBRIDGE W. STEVENS, a citizen of the United States, residing at Baltimore city, in the State of Maryland, have invented certain new and useful Improvements in Igniters for Explosion-Engines, of which the following is a specification.

My invention relates to igniters for closing the electric circuit by which the spark is produced for exploding the charge of an explosion or internal combustion engine and it consists mainly in the novel construction and arrangement of devices operated upon by a rotary cam whereby the closure and opening of the electric circuit to produce the spark is effected in a simple and practical way and in a uniform manner irrespective of the speed of the engine and by which also damaging strain to and the breakage of the contact devices are avoided in the event of a back-fire and reversal of the cam shaft, as hereinafter more fully described with reference to the drawing in which,

Figure 1 is a sectional view taken on the line 1—1 of Fig. 2; Figs 1^a and 1^b show different positions of the cam, and Fig. 2 is a section taken on line 2—2 of Fig. 1.

In the drawing X represents a disk-shaped frame formed with a central hub-portion X' and an offsetting and perforated arm J, whose function will be hereinafter described.

The disk portion of the frame is formed with lugs x to which is connected, by screws y, a cup-shaped casing Y within which my igniter devices are contained. These igniter devices consist of a shaft R arranged with ball bearings r r r r, within the hub-portion. This shaft has at one end a socket portion with clamp screw s by which it is connected in alignment to the cam actuating shaft and at the other end the shaft R is screw threaded and projects into the casing Y and has screwed on to it and rigidly secured to it a cam head A. This cam head has on it one or more cam nubs or projections a, said cam nubs corresponding in number to the number of cylinders in the engine and each nub serving to open and close the spark-making circuit for its own cylinder.

On the frame plate X at one side of the cam head A there is arranged a pivot screw K on which oscillates a block M carrying on one side a leaf spring E and on the other

side a compound member consisting of an arm C substantially parallel to the spring E but having a flattened tubular end portion forming a sheath or guide in which fits and freely slides the shank t of a right angular tappet arm B which is acted upon by the nubs of the cam to produce a compound motion; that is to say, with the cam shaft revolving in the direction of the arrow in Fig. 1, the nubs of the cam first pull on the tappet arm B and pull out the shank t of the arm from its tubular sheath or guide in arm C, and then as the cam nub passes by the end of the tappet arm B it forces the tappet arm B and arm C to the right about its pivotal center K and, rocking the block M, also causes the spring contact E with its platinum point d to move to the right. As it so moves to the right, said platinum point is brought into contact with the adjacent platinum point D of a screw V and, the two platinum points being terminals of the electric circuit, the latter is made or broken by the alternate contact and separation of the platinum points to produce the spark in the well known way. The contact point D is made adjustable to or from the other contact point d to time within certain limits the period of contact by the adjustment of the screw V. This screw is held in a split-head P whose two jaws are clamped together by a screw I to firmly hold the screw V to its adjustment. The screw threaded stem T of the clamp head passes through a non-conducting bushing U in the disk frame X and is clamped in place by jam nuts S.

In connection with the vibrating arm C and the sliding and vibrating tappet arm B, two coil springs G and H are employed. Both of these at their outer ends are anchored to studs or screws on the frame plate and at their inner ends the spring G is connected to the tappet arm B and serves to slide its shank back into its sheath or guide after the cam nub has passed by the end of the arm, while the inner end of spring H is connected to the arm C or some part of block M and serves to bring the arm C back again toward the cam after the nub has passed and thus separate the contact d from D. As the spring G is arranged at an angle to the arm C, it will be seen that it alone will perform the double function of retracting the tappet arm B and also rocking the arm C toward

the cam A. The spring H acts in a supplementary way to make a quick return of arm C toward cam A after a nub a has passed the tappet arm B, but said spring H may be dispensed with.

The contact-making member E and the compound cam-actuated member C are mounted upon the block M, located at one side, and vibrate about the single pivotal center K, swinging exclusively about one and the same center and the contact making member E and the compound cam-actuated member C project in substantially parallel position to each other up to a line between 10 the cam A and the stationary contact D.

From the foregoing description it will be seen that with the cam shaft revolving normally in the direction of the curved arrow, when a nub a strikes the tappet arm B it 20 first pulls it out of its sheath a given distance against the tension of spring G, and then as the nub passes the end of tappet arm B, it projects the tappet arm, with arm C and spring E bearing contact d, to the right, 25 until the latter touches contact D and closes the circuit. After the cam nub passes the tappet arm, spring G draws up the tappet arm shank into its guide or sheath and spring H acting in conjunction with G draws 30 the arm C back against a stop F to open contact between d and D to produce the spark and put the tappet arm in proper relation for the next closure of a circuit, for the next cylinder to be fired. That this action may 35 be better understood, and the distinctive features of my invention more clearly pointed out, I now refer to Figs. 1^a and 1^b. In Fig. 1^a a cam nub a' has pulled down the tappet arm B to its limit, and the highest point of 40 the cam is just about to project the tappet arm B and arm C to the right to close the circuit. As the cam nub passes a little farther, as in Fig. 1^b, the tappet arm B is projected to the right, as indicated by the dotted lines, and then as the tappet arm rides 45 on the curved part of the cam, the spring G pulls up tappet arm B immediately and spring H brings it in toward the center of cam head A. This movement of the tappet arm from the dotted position in Fig. 1^b to the full line position is not affected by the progressive movement of the cam, but is produced by spring action independent of 50 the speed of the cam and as this movement of arm C to the left is the opening movement 55 of contact spring E, it will be seen that the breaking of the circuit, to produce the spark, is independent of the speed of the cam shaft and is uniform for all speeds of the engine;

60 that is to say, the separation of contact points d and D to produce the spark is effected by a spring actuated movement independent of the progressive movement of the cam. As shown, there are four cam nubs 65 for a four cylinder engine. There may,

however, be only one cam nub or any number of cam nubs to correspond with any number of cylinders in the engine.

With my invention, if there should be any back-firing of the engine and a reversal of 70 the cam shaft, the nubs do not strike against and break any unyielding part, but the tappet arm B and arm C simply yield backward against the tension of spring H without doing any damage.

In the upper part of Fig. 2 is shown the distributor for the high tension current for which I make no claim. The part 3 is a non-conducting block mounted on and revolving with shaft R and carrying spring 2. This 80 spring bears constantly against the metal terminal 1 of the secondary wire and as block 3 revolves with the shaft R, the spring 2 delivers the spark to the terminals 4 and 5 of the cylinders connected thereto. To advance or retard the spark, it is only necessary through arm J to rotate casing Y with the contacts 1, 5, 4, in relation to the revolving spring 2, as is well known.

I claim—

1. An igniter device for making and breaking an electric circuit for explosion engines, comprising a rotating cam member and a compound member acted upon thereby consisting of a pivoted arm having a guide, 95 a sliding tappet arm arranged in said guide, a spring mechanism for holding the tappet arm in its guide and for holding the tappet arm and guide against the cam, a contact bearing member combined with said parts and partaking of their movements and a relatively stationary coöperating contact.

2. An igniter device for making and breaking an electric circuit for explosion engines, comprising a rotating cam member 105 and a compound member acted upon thereby consisting of a pivoted arm having a guide, a sliding tappet arm arranged in said guide, a spring mechanism for holding the tappet arm in its guide and for holding the tappet 110 arm and guide against the cam, a contact bearing member combined with said parts and partaking of their movements and a relatively stationary coöperating contact consisting of a screw carrying a platinum 115 bearing, bifurcated jaws embracing the screw, a clamp screw for bringing the jaws together and means for mounting and insulating said parts.

3. An igniter device for making and 120 breaking an electric circuit for explosion engines, comprising a rotating cam member, a compound member acted upon thereby consisting of a pivoted block having on one side an arm bearing a longitudinal guide, a 125 tappet arm having a shank sliding in said guide, a spring for holding the tappet arm up in its guide, another spring for holding the tappet arm and its guide against the cam, a spring member bearing a contact point 130

and attached to the pivoted block and a stationary contact point.

4. An igniter device for making and breaking an electric circuit for explosion engines, comprising a rotating cam member, a compound member acted upon thereby consisting of a pivoted block having on one side an arm bearing a longitudinal guide, a tappet arm having a shank sliding in said 10 guide, a spring for holding the tappet arm up in its guide, another spring for holding the tappet arm and its guide against the cam, a spring member bearing a contact point and attached to the pivoted block and 15 a stationary contact point, the spring contact member and the tappet bearing member being substantially parallel.

5. An igniter device for making and breaking an electric circuit for explosion 20 engines, comprising a rotating cam member and a compound cam-actuated member, consisting of a pivoted arm having a longitudinal guide and a sliding tappet arm arranged in said guide, a spring mechanism 25 for holding the tappet arm retracted in its guide and for holding the tappet arm and guide against the cam, a contact bearing member hung upon the same pivotal center as the compound member and permanently 30 connected to the latter for movement therewith and a relatively stationary coöperating contact.

6. A device for making and breaking an electric circuit, consisting of a rotating cam 35 member, a stationary contact point set op-

posite the same, a pivoted block set to one side of a line between the cam and contact and having attached thereto a contact making member and a compound cam-actuated member, both projecting to the line between 40 the cam and stationary contact, the compound cam-actuated member having a guide containing a sliding tappet projection acted upon by the cam and a spring mechanism for pulling the tappet into its guide and 45 against the cam.

7. A device for making and breaking an electric circuit, consisting of a rotating cam member, a stationary contact point set opposite the same, a pivoted block set to one 50 side of a line between the cam and contact and having attached thereto a contact making member and a compound cam-actuated member, both projecting to the line between the cam and stationary contact, the compound cam-actuated member having a guide 55 containing a sliding tappet projection acted upon by the cam and a spring mechanism for pulling the tappet into its guide and against the cam, the compound cam-actuated member and the contact making member being arranged substantially parallel to each other.

In testimony whereof I affix my signature in presence of two witnesses.

ELBRIDGE W. STEVENS.
